By his Attorney W. T. Ciswell

UNITED STATES PATENT OFFICE.

LAURENS P. DIXON, OF NEW YORK, N. Y.

SOCKET FOR ELECTRIC LAMPS.

1,214,439.

Specification of Letters Patent. Patented Jan. 30, 1917.

Application filed January 6, 1914. Serial No. 810,603.

To all whom it may concern:

Be it known that I, LAURENS P. DIXON, a citizen of the United States, and a resident of New York, county and State of New York, have invented a certain new and useful Improvement in Sockets for Electric Lamps, of which the following is a full, clear, and exact specification.

This invention relates to a class of devices 10 adapted to be used in conjunction with electric lighting systems.

My invention has for its object primarily to provide a socket designed to be employed for permitting a number of electric lamps 15 to be mounted thereon whereby the lamps may be lighted separately or collectively from an electric circuit, and wherein is provided a casing made of material which is a non-conductor of electricity, this casing being composed of a middle section and two 20 recessed tubular end sections so that when assembled separate chambers are provided therein. Through the end sections are formed registered passages, each of which 25 communicates with one of the chambers, and each passage is adapted to receive one of the electric lamps.

Another object of the invention is to provide at spaced intervals in each chamber a 30 pair of contacts, and the contacts of each pair are relatively arranged so as to be engaged by the contacts of the lamps when applied to the socket.

Still another object of the invention is to 35 provide in openings formed in the middle section tubular metal receivers which are connected to the contacts for permitting the electric circuit to be transmitted thereto through the medium of plugs provided on 40 the ends of the wire of the electric circuit leading to the socket, and which are removably inserted in the receivers whereby the lamps may be lighted collectively, or separately.

With these and other objects in view, the 45 invention will be hereinafter more particularly described with reference to the accompanying drawing which forms a part of this specification, in which similar characters of reference indicate corresponding parts in all the views, and will then be pointed out in the claims at the end of the description.

In the drawing, Figure 1 is a fragmentary 50 view, showing a top plan of one form of socket embodying my invention. Fig. 2 is

a longitudinal vertical section taken on the line II—II of Fig. 1. Fig. 3 is a plan of the middle section of the casing of the socket. Fig. 4 is a plan of one of the end sections 60 of the socket. Fig. 5 is a plan of the second end section of the socket. Fig. 6 is a plan of one of the contacts used in the socket. Fig. 7 is an edge view thereof. Fig. 8 is a plan of one of the other contacts used in 65 the socket. Fig. 9 is an edge view thereof. Fig. 10 is a fragmentary view showing an enlarged side elevation, partly in section, of one of the tubular receivers employed in the section. Fig. 11 is an enlarged elevation, partly in section, of one of the plugs employed on the ends of the wires of the electric circuit. Fig. 12 is a fragmentary view, showing the lower part of a form of 70 electric lamp adapted to be used in conjunction with the socket, and Fig. 13 is an inverted plan of the socket.

The socket has a casing 10 made of porcelain, or other material which is a non-conductor of electricity, and said casing is preferably composed of a middle section 11, and two recessed tubular end sections, or sleeves 12 and 13. The middle section 11 is in the form of a circular disk having two openings 14 and 15 at diametrically opposite parts 80 thereof, and these openings are adjacent to the edge of the disk. In proximity to the edge of the disk and approximately midway between the openings 14 and 15 is an opening 16, and contiguous to the edge of the 85 disk at parts thereof which are opposite to the opening 16 are two similar spaced openings 17 and 18. Also through the disk and adjacent to each of the openings 16, 17, 18 are provided holes, as 19, 20, 21, respectively. 90

The end section, or sleeve 12 has a tubular part 22 to provide a passage 23 therethrough. Extending at a right angle from the outer periphery of the tubular part is an annular plate 24 having a concentric flange 100 25 projecting from its outer edge in an opposite direction from the tubular part 22, and through diametrically opposite parts of the annular plate are two openings 26 and 27 adapted to be registered with the openings 14 and 15 of the disk 11. The sleeve 12 is disposed relatively to the disk 11 so that the free edge of its flange 25 will rest against one surface of the disk whereby the plate 24 and the tubular part 23 will be spaced from 105 the disk to provide a chamber 28 communicating with passage 23 of the section, or 110

sleeve 12. This wall of the passage is lined with copper or other material, as 29, which is a conductor of electricity, and this lining may be interiorly threaded, or provided with 5 a slot, as 30, for reception of the pin 31 of the neck 31^a of a well known type of electric lamp, as 32 Figs. 12 and 13.

The end section, or sleeve 13 is formed with a tubular part 33 whereby a passage 34 is provided therethrough. Projecting at a right angle from the outer periphery of the tubular part 33 is an annular plate 35 provided with a concentric flange 36 extending from its outer edge in an opposite direction 15 from the tubular part 33, and through diametrically opposite parts of this annular plate are two openings 37 and 38 which are adapted to be registered with the openings 14 and 15 of the disk 11. Also through the 20 annular plate 35 approximately midway between the openings 37 and 38 is an opening 39 adapted to be registered with the opening 16 of the disk, and at spaced intervals in opposite parts of the annular plate are two 25 openings 40 and 41, each of which is adapted to be registered with one of the openings 17 and 18, respectively, of the disk 11. The wall of the passage 34 is lined with copper, or other material, as 41^a, which is a conductor of electricity and this lining may be interiorly threaded, or provided with a slot, not shown, for reception of the pin of the neck of a second electric lamp of a similar 30 type to the lamp 31. When the sleeve 13 is applied to the disk 11 it is disposed, like the sleeve 12, relatively to the disk so that the free edge of its flange 36 will rest against the second surface of the disk. The annular plate 35 will thereby be spaced from 35 the disk to provide a second chamber 42 which communicates with the passage 34 of this sleeve. When these parts are thus assembled and arranged so that the openings 40 45 14 and 15 of the disk 11, the openings 26 and 27 of the sleeve 12, and the openings 37 and 38 of the sleeve 13 are in register, the parts are secured together by passing bolts 43 and 44 through the registered openings. 50 Through the holes 19, 20, 21, of the disk 11 are provided pins, or screws 45, 46, 47 all of which are of sufficient lengths so that both ends of each pin extends beyond both surfaces of the disk and into the chambers 55 28 and 42 of the casing. On the end of the pin 45 extending into the chamber 28 is held a contact 48 which is preferably in the form of a metal strip disposed in this chamber so as to be engaged by one of the contacts of the electric lamp when mounted in the passage 23 of the sleeve 12, and on the end of the pin 46 projecting in this chamber is held a second contact 49 which is also in the form of a metal strip disposed in opposing 60 relation to the contact 48 for being engaged by the second contact of the electric lamp. 65

Also on the end of the pin 45 extending into the chamber 42 is held a contact 50 in the form of a metal strip disposed in this chamber so as to be engaged by one of the contacts of a second electric lamp when mounted 70 in the passage 34, and on the end of the pin 47 projecting in said chamber 42 is held a contact 51 in the form of a metal strip arranged in opposition to the contact 50 for engagement with the other contact of the 75 second electric lamp.

Through the contacts 48 and 50 are openings which are in register with the opening 16 of the disk 11. Also through the contact 49 is an opening in register with the opening 17 of the disk, and through the contact 51 is an opening in register with the opening 18 of the disk. In these sets of openings are provided tubular receivers, as 56, 57, 58, one of the receivers, being held in each 80 set of the openings, and the passages through the receivers are in register respectively with the openings 39, 40, 41 of the sleeve 13. All of the receivers 56, 57, 58 are in the forms of metal tubes of sufficient lengths so that the ends of each tube 85 will extend a slight distance into the chambers of the casings, and by bending the edges of the free ends of the tubes so as to overlap the opposed surfaces of the disk and 90 the contacts the tubular receivers will be held in the casing against displacement for serving as conductors of electricity to the contacts. Each of the tubular metal receivers serves to removably admit therein 95 one of the plugs, as 59, 60, 61, provided upon one of the corresponding ends of wires, as 62, 63, 64, of an electric circuit, not shown, whereby the current of the circuit may be transmitted to the contacts of the socket, 100 and all of the wires may be suitably arranged to lead from a single source of electricity supply, or from two separate sources 105 of electricity supply. The plugs may serve independently for opening, or closing the 110 circuit to contacts of the socket, or the plugs may be removably disposed so as to remain in the tubular receivers, and the circuit may then be closed by any suitable means provided therein. When it is desired to employ the plugs for closing the circuit to 115 light an electric lamp in engagement with the contacts in the chamber 28 of the casing the plugs 59 and 60 are inserted through 120 the openings 39 and 40 of the sleeve 13 and into the receivers 56 and 57 the current will then be transmitted to this lamp over the wires 62 and 63, or when it is desired to close the circuit for lighting an electric lamp in engagement with the contacts of the 125 chamber 42 of the casing the plug 60 is removed from its receiver, and the plug 61 is inserted through the opening 41 of the sleeve 13 and into the receiver 58. In order to close the circuit to light both of the lamps 130

all of the plugs are inserted in their respective receivers, and the opening and closing of the circuit to the lamps may then be controlled by the means provided in the circuit for use for this purpose. By the means described all of the electric lamps may be lighted separately or collectively.

In the foregoing description, I have embodied the preferred form of my invention, but I do not wish to be understood as limiting myself thereto, as I am aware that modifications may be made therein without departing from the principle, or, sacrificing any of the advantages of this invention, therefore I reserve to myself the right to make such changes as fairly fall within the scope of the appended claims.

Having thus described my invention, I claim as new and desire to secure by Letters Patent:—

1. In a socket for electric lamps, the combination with a central disk of two aligned lamp socket sleeves removably secured to opposite sides of said disk, said sleeves each having a metallic lining for contact with the end of an electric lamp, flanges extending outwardly from the opposed ends of said sleeves with turned peripheral edges resting on the central disk for providing chambers between the flanges and the central disk, with means for securing the sleeves to the central disk, two electrical contacts secured on each side of the central disk within said chambers, each of said chambers having an opening therein for retaining the end of a metallic sleeve, said central disk having openings therethrough and metal sleeves disposed through said openings and through the openings of the contacts, the

flange of one of the socket sleeves having three openings to admit plugs for insertion in the said sleeves of the central disk and the contacts, substantially as described, and for the purpose specified.

2. A double ended lamp socket comprising a central disk, cup shaped lamp receivers attached to the faces of said disk, electrical contacts mounted on each face of said disk and adapted to contact with a lamp when in place within said receivers, a metallic sleeve passing through said disk and connecting any two contacts on opposite faces of said disk, and a separate sleeve for each of the remaining contacts, said sleeves being adapted to receive either the positive or the negative plugs of an electric circuit, whereby either or both of the lamps may be lighted as desired.

3. A lamp socket comprising a central disk, lamp receivers attached to each face of said disk, two electric contacts mounted on each face of said disk and adapted to make a contact with a lamp when secured within said receivers, a metallic sleeve connecting any two contacts on opposite sides of said disk, and separate sleeves connected to each of the two remaining contacts, said sleeves being adapted to receive the positive and negative plugs of an electric circuit, whereby either or both of the lamps may be lighted as desired.

This specification signed and witnessed this fifth day of January, A. D. 1914.
